WARP BEAM FOR LOOMS

Carl P. Bergstrom, Millbury, Mass., assignor to
Crompton & Knowles Loom Works, Worcester,
Mass., a corporation of Massachusetts

Application August 25, 1950; Serial No. 181,535

10 Claims. (Cl. 242—124)

1

This invention relates to improvements in warp beams for looms and it is the general object of the invention to provide a beam barrel formed with internal radial webs having driving engagement with lugs or the like on heads secured to the ends of the barrel.

A warp beam generally comprises an elongated cylindrical barrel having at the ends thereof supporting gudgeons for mounting the beam in a winding machine and also in a loom. These gudgeons are supported by heads secured to the ends of the barrel preferably in such manner that the heads and gudgeons turn with the barrel but can be removed from it for repair or renewal.

It is an important object of the present invention to provide a beam barrel with webs running lengthwise thereof and fitting into slots between driving lugs or the like formed on the heads. Tie rods extending through the barrel hold the heads to the ends of the barrel with the webs fitting into the slots.

It is a further object of the invention to provide a beam barrel having lengthwise integral webs engaging head carried lugs or the like which extend in the direction of the length of the barrel so that the heads when moved endwise of the barrel can establish driving connection between the webs and lugs.

With these and other objects in view which will appear as the description proceeds, the invention resides in the combination and arrangement of parts hereafter described and set forth.

In the accompanying drawings,

Fig. 1 is an elevation of a warp beam made according to the present invention and showing one form of head at the right hand end and another form of head at the left hand end thereof;

Figs. 2 and 3 are enlarged vertical sections on line 2—2 and 3—3, respectively, of Fig. 1;

Fig. 4 is an enlarged longitudinal section of line 4—4, Fig. 2;

Fig. 5 is a transverse section on line 5—5, Fig. 4;

Fig. 6 is a perspective view of one pair of lugs on the form of head shown for instance in Fig. 4, and

Fig. 7 is a view similar to Fig. 4 but showing the other form of head at the left hand end of the beam as viewed in Fig. 1.

Referring to the drawings, barrel 1 on which the warp (not shown) is wound comprises an outer shell 2 formed as a cylinder and connected by radial webs 3 to an inner core or tube 4 having a bore 5. The shell 2 and tube 4 are preferably concentric and are integral with the webs 3. The barrel may be formed as an extrusion and although three webs are shown in Fig. 3 the in-

2

vention is not limited to a barrel having this number of webs.

The head H shown at the right hand end of Fig. 1 is formed with a flange 10 having integral therewith an outwardly extending hub 11 formed with a bore 12 preferably of the same diameter as the bore 5. The flange 10 has a rim 13 which abuts the adjacent end of shell 2, see Fig. 4. Extending inwardly from the flange 10 is a second hub or collar 15 integral with the flange and telescoped or fitted into the shell 2.

The collar 15 in the present instance is made in three arcuate parts 16 extending circumferentially around the axis of the barrel. Adjacent ends of the parts 16 are formed with lugs 17 separated by radial web receiving slots 18 which are of a width substantially the same as the thickness of the webs 3. Each slot is formed by a pair of lugs 17, and the latter are located on opposite sides of the associated web. Where the webs join the shell 2, see Fig. 5, they are formed with fillets 19, and in order to accommodate the fillets the lugs 17 are beveled as at 20. It is to be understood that the collar will have a slot 18 for at least one of the webs 3 and preferably for all of the webs.

The parts 16 of collar 15 may if desired be formed with cylindrical surface 25 concentric with the barrel and fitting closely into the adjacent end of the shell 2 between the webs 3. The surfaces 25 serve to center the head H with respect to the barrel. When thus centered the bores 5 and 12 are in alignment to receive a gudgeon 26 which is preferably driven into the hub 11 and extends into the bore 5, as shown in Fig. 4.

The head H at the left hand end of Fig. 1 and shown more particularly in Fig. 7 is similar to head H except that it has provision for receiving a friction strap or the like (not shown) forming some part of the let-off mechanism for a loom. The head H has a flange 30 formed integrally with a drum 31 around a part of which at least a friction strap can be wrapped when the warp beam is in a loom. The head H has an outwardly extending hub 32 similar to hub 11 and an inwardly extending hub or collar 33 similar to hub or collar 15. A second gudgeon 34 similar to gudgeon 26 may be driven into hub 32 and extend into the bore 5 in a manner similar to that already described in connection with Fig. 4.

Two tie rods 35 and 36 are provided to serve as retaining or holding means to hold the heads H and H¹ to their respective ends of the barrel. These tie rods extend through the flanges 10 and 30 and have their ends screw-threaded to receive nuts 37 which when tightened hold the heads H

and H1 firmly to the ends of the barrel with the ends of the webs 3 in the slots 18 between the pairs of lugs. These tie rods extend through the barrel parallel to but spaced from the webs 3. If desired, more than the two tie rods shown in Figs. 2 to 5 may be employed.

As shown in Fig. 5 the three webs are equiangularly spaced around the axis of the barrel and by their entry into the radial slots 18 serve to center the head with respect to the axis of the barrel. It is for this reason that the collar 15 may if desired be made without the cylindrical surfaces 25. It is preferred, however, to use the cylindrical surface 25 to insure true centering of the heads with respect to the barrels so that the gudgeons may properly fit into bore 5.

It will be understood that the lugs 17 of each pair of lugs have lateral engagement with the opposite sides of the corresponding web 3, and all the lugs extend in the direction of the length of the barrel so that the webs 3 will fit into the slots 18 when the head is moved endwise toward the barrel. The webs and lugs cooperate to require the head and barrel to turn in unison and prevent relative angular movement between them.

If desired the head H may be provided with lugs 40 extending outwardly from the web 10 for cooperation with a letoff mechanism designated generally at L and indicated by dot and dash lines in Fig. 1. This letoff mechanism may for instance be similar to that shown in Payne Patent No. 1,803,143. The external surface of the barrel 1 may be provided with screw threads 45 to receive warp flange 46 between which the warp threads are wound.

From the foregoing it will be seen that the invention sets forth a simple warp beam the barrel of which is provided with longitudinally extending and preferably radial webs 3 which fit into slots 18 between driving lugs 17 on heads held to the end of the barrel by tie rods. The lugs extend along and preferably on opposite sides of the webs and with the latter establish driving connections between the heads and the barrel. The lugs fit around and slide along the webs when the heads are moved toward their respective ends of the barrel. The barrel is preferably although not necessarily made as an extrusion and the webs 3 are preferably spaced equiangularly around the axis of the barrel. While it is preferable to have a pair of lugs for each web 3 it will be understood that a single pair of lugs in engagement with one of the webs will be sufficient to establish driving connection. When only a single pair of lugs is used it is desirable to have the cylindrical surfaces 25 on the head, but this surface may be omitted if there is a pair of lugs for each web and reliance is placed on the close fit between the webs and their pairs of lugs to center the head. If only two slots 18 are used they will nevertheless center the head on the barrel due to the fact that the webs entering the slots lie in oblique planes. When it is desired to remove the head the tie rods can be loosened and the lugs will slide off the webs as the head is moved endwise away from the barrel.

Having thus described the invention it will be seen that changes and modifications of the foregoing specific disclosure may be made without departing from the spirit and scope of the invention.

What is claimed as new is:

1. In a warp beam, a barrel comprising an outer cylindrical shell and an inner tubular core con-

centric with the shell and a radial web extending lengthwise of the barrel connecting said shell and core, a head at one end of the barrel having parts thereof extending in the direction of the axis of the barrel along opposite sides of said web to cause angular movement of the barrel when the head is turned.

2. In a warp beam, a barrel comprising an outer cylindrical shell and an inner tubular core concentric with the shell and a radial web extending lengthwise of the barrel connecting said shell and core, a head at one end of the barrel, a pair of spaced lugs on the head extending along opposite sides of the web in the direction of the length of the barrel, and retaining means holding the head on the barrel and maintaining the lugs on said opposite sides of the web.

3. In a warp beam, a barrel comprising an outer cylindrical shell and an inner tubular core concentric with the shell and a radial web extending lengthwise of the barrel connecting said shell and core, a head at one end of the barrel, a pair of lugs on the head spaced by a radial slot into which the web extends, and retaining means holding the head on the barrel and maintaining the lugs on said opposite sides of the web with the latter in said slot.

4. In a warp beam, a barrel comprising an outer cylindrical shell and an inner tubular core concentric with the shell and a plurality of radial webs extending lengthwise of the barrel connecting said shell and core, a head on one end of the barrel formed with radial slots to receive said webs, and means holding the head on the barrel with the webs extending into said slots.

5. In a warp beam, a barrel comprising an outer cylindrical shell and an inner tubular core concentric with the shell and a plurality of radial webs extending lengthwise of the barrel connecting said shell and core, a head on one end of the barrel having lugs to extend along said webs in the direction of the length of the barrel, and means holding the head on the barrel with the lugs in position for engagement with said webs to prevent angular movement of the head relative to the barrel around the axis of the barrel.

6. In a warp beam, a barrel comprising an outer cylindrical shell and an inner tubular core concentric with the shell and a plurality of radial webs extending lengthwise of the barrel connecting said shell and core, a head on one end of the barrel having a pair of lugs for each web, the lugs of each pair extending along opposite sides of the corresponding web in the direction of the length of the barrel, and means holding the head on the barrel with each web extending between the lugs of the corresponding pair of lugs.

60 7. In a warp beam, a barrel comprising an outer cylindrical shell and an inner tubular core concentric with the shell and at least two radial webs lying in oblique planes extending lengthwise of the barrel and connecting the shell and core, and a head held on one end of the barrel having a pair of spaced lugs thereon for each web, the lugs of each pair being separated by a radial slot into which the corresponding web extends, said lugs and webs cooperating to prevent movement of the head transversely and angularly with respect to the barrel.

8. In a warp beam, a barrel comprising an outer cylindrical shell and an inner tubular core concentric with the shell, a plurality of at least three radial webs extending lengthwise of the

barrel and equiangularly spaced around the axis of the barrel, and a head held to one end of the barrel having a pair of lugs for each web, the lugs of each pair extending in the direction of the length of the barrel along opposite sides of the associated web, said webs and pairs of lugs cooperating to prevent transverse and angular movement of the head relative to the barrel.

9. In a warp beam, a barrel comprising an outer cylindrical shell and an inner tubular core concentric with the shell and a plurality of radial webs extending lengthwise of the barrel connecting said shell and core, a head on one end of the barrel formed with radial slots to receive said webs, the head when moved toward the adjacent end of the barrel along the axis of the latter with the webs aligned with the slots causing the webs to enter the slots, and means holding the head on the barrel with the webs entering into said slots.

10. In a warp beam, a barrel comprising an outer cylindrical shell and an inner tubular core

concentric with the shell and a plurality of radial webs extending lengthwise of the barrel connecting said shell and core, a head on one end of the barrel formed with radial slots to receive said webs, the head having circumferential surfaces in contact with the barrel extending between said slots and fitting into the shell between said webs to center the head on the barrel, and means holding the head on the end of the barrel with the webs extending into said slots.
